UNITED STATES PATENT OFFICE.

WILLIAM A. BOWMAN, OF REPUBLIC, WASHINGTON.

NECK-YOKE ATTACHER.

1,121,461.

Specification of Letters Patent. Patented Dec. 15, 1914.

Application filed April 18, 1914. Serial No. 832,781.

To all whom it may concern:

Be it known that I, WILLIAM A. BOWMAN, a citizen of the United States, residing at Republic, in the county of Ferry and State of Washington, have invented new and useful Improvements in Neck-Yoke Attachers, of which the following is a specification.

This invention is an improved neck yoke attacher which also forms a cap for the front end of a vehicle tongue, the object of the invention being to provide an improved device of this character by means of which a neck yoke may be attached to a vehicle tongue at the extreme front end of the latter and thereby prevent the tongue from projecting forwardly of the neck yoke and forming an obstruction which is likely to catch the lines.

The invention consists in the construction, combination and arrangement of devices hereinafter described and claimed.

In the accompanying drawings:—Figure 1 is a vertical longitudinal sectional view of the front portion of a vehicle tongue provided with a neck yoke attacher and cap constructed in accordance with my invention. Fig. 2 is a transverse sectional view of the same.

For the purposes of this specification the front portion of a vehicle tongue is indicated at 1. In accordance with my invention I provide an iron or cap 2 which is fitted on the front end of the tongue and is secured thereto by means of rivets 3. In the lower side of the cap or iron, at the front end thereof, is formed a substantially V-shaped hook 4 which comprises a vertical front arm 5 and an inclined rear arm 6. The vertical front arm is provided at its upper end with a forwardly projecting lip 7. This lip is at the lower side of the cap. The cap is provided in its lower side with a longitudinal slot which extends through its front end and in the said slot is fitted a longitudinally movable bolt 8. This bolt bears on the lower side of the cap or iron and is provided with slots 9 through which the rivets 3 extend, the said slots permitting longitudinal movement of the bolt as will be understood. At the front end of the bolt is a downwardly extending arm 10 at the lower end of which is a rearwardly extending lip 11. When the bolt is drawn forwardly its arm 10 and lip 11 are spaced from the arm 5 and lip 7 of the hook thereby forming a

tortuous space or passage between the front end of the bolt and the hook and which adapts a neck yoke ring placed around the tongue and its cap to be arranged with its lower side between the arms 5 and 6 of the hook. The bolt is then moved rearwardly, thereby closing the arm 10 of the bolt against the arm 5 of the hook and arranging the lip 11 under the lip 7 and hence securing the neck yoke ring against casual detachment from the cap or iron. To secure the bolt in closed position the same is provided near its rear end with an opening 12. I also provide a locking pin 13 which passes through and is longitudinally movable in an opening in the iron or cap and in the tongue and this pin is engaged with the said opening 12 and is held in engaged position therewith by means of a spring 14.

It will be understood from the foregoing that when the neck yoke has been thus attached to the pole it is arranged at the front end thereof so that the pole does not project beyond the neck yoke and hence does not form an obstruction at that point and cannot catch the lines. In order to release the neck yoke it is only necessary to first withdraw the pin 15 against the tension of the spring 14, then draw the bolt 8 forwardly and then remove the neck yoke ring from the hook.

Having thus described my invention, I claim:

The herein described neck yoke attacher comprising a cap for application to the front end of a pole, and formed on its under side at its front end with a hook to engage and hold a neck yoke ring, said hook having an arm projecting from one side of said cap, a longitudinally movable bolt arranged in a slot in the lower side of the cap and having an arm to close against said arm of the hook, said bolt having longitudinal slots, and also having an opening, rivets to secure the cap to the pole and arranged in the slots of the said bolt and a spring pressed pin to engage the opening of the bolt and lock the latter in closed position.

In testimony whereof I affix my signature in presence of two witnesses.

WILLIAM A. BOWMAN.
